GAS MAKING APPARATUS

Henry O. Loebell, Malba, N. Y., assignor to
Henry L. Doherty, New York, N. Y.

Original application May 23, 1923, Serial No.
640,828. Divided and this application May 23,
1931. Serial No. 539,600, and in Great Britain
January 31, 1924

7 Claims. (Cl. 202—88)

This invention relates to the manufacture of fuel gas, and more particularly to a method of making gas for industrial purposes by the complete gasification of coal.

The gas which is now being commonly burned for industrial heating purposes is known as a producer gas which has a comparatively low calorific value. This gas is manufactured by a process of burning coal wherein inert materials such as nitrogen of the air used and carbon dioxide formed by combustion of carbon with the air remain in the gas so that 55% to 65% of the gas is inert material. Producer gas has a limited use for industrial heating purposes, because it has a low flame temperature, a low calorific value and a slow flame propagation. Some heating processes require comparatively high flame temperatures and an attempt has been made to make a blue water gas for this purpose. The so called "blue gas" has a comparatively high flame temperature and a comparatively low percentage of inert materials, but the cost to manufacture blue water gas is very high and the yield of the blue water gas from a ton of coal is comparatively small as compared with the amount of producer gas which can be made from a ton of coal.

One object of the present invention is to provide a method of manufacturing an industrial fuel gas which has a comparatively high flame temperature, a rapid flame propagation, and a calorific value which adapts it for practically all industrial heating purposes.

Another object of the invention is to provide a method of making industrial gas by which valuable by-products may be recovered and at the same time a gas will be produced which is free of contaminating and deleterious materials.

A further object of the invention is to provide a process of making industrial gas which is efficient in the conservation of heat and which may be completely controlled to control the character of gas being made.

With these and other objects and features in view, the invention consists in the improved gas making process hereinafter described and specifically defined in the claims.

The various features of the invention are illustrated in the accompanying drawings, in which:—

Fig. 1 is a view in vertical section with parts in elevation of a gas generator embodying the preferred form of the invention;

Fig. 2 is a top plan view of the generator shown in Fig. 1;

Fig. 3 is a vertical sectional view of the waste

heat boiler used with the generator, the section being taken on the line 3—3 of Fig. 2;

Fig. 4 is a horizontal sectional view taken on the line 4—4 of Fig. 5, illustrating the mechanism for removing coke from the bottom of the generator; and

Fig. 5 is a vertical sectional view taken on the line 5—5 of Fig. 4 to illustrate the coke discharging mechanism.

The method of making fuel gas embodying the preferred form of the invention may be carried out in the apparatus illustrated in the drawings substantially as follows: Fuel to be carbonized, which is preferably a coking grade of bituminous coal in mixture with coke, is placed in a hopper 10 and is intermittently introduced into the upper part of a generator shaft 12 by means of a pocket 14 and intermittently operated valves 16 and 18. When the valve 16 is moved downwardly, the pocket 14 will be filled with coal. At this time the valve 18 is closed. Thereupon the valve 16 will be closed and the valve 18 will be opened to allow the fuel to pass into the top of the generator shaft. The fuel discharging from the pocket 14 passes around a central gas off-take 20 and is distributed into the top of an upright column of fuel supported in the shaft 12. The upper portion of the fuel column or approximately the portion above the lower end of the gas off-take 20, comprises a coal carbonizing zone. The portion of the fuel column below the bottom of the off-take 20 and extending downwardly a short distance below an offset portion 22 in the shaft 12 constitutes a blast zone in which the fuel is maintained at a comparatively high temperature by partial combustion thereof. The portion of the fuel column from the bottom of the blast zone to the bottom of the column is a cooling or quenching zone in which the unburned carbonized fuel and ashes are quenched before being removed from the generator. The unburned carbonized fuel is continuously discharged from the bottom of the column and continuously moves downwardly through the shaft.

The gas is made by several distinct reactions which take place between the fuel and the air and steam used for making the gas. The first reaction is an exothermic reaction which takes place when air is used to burn carbon of the fuel, according to the following equation:

A second reaction takes place between the carbon of the fuel bed and the carbon dioxide which is

formed by the combustion of air, in accordance with the following equation, which is endothermic:

5 A third reaction takes place between carbon of the fuel bed and steam which is introduced at the fuel bed, the reaction being endothermic, as follows:

10 A fourth reaction is that which takes place when the volatile material, principally hydrocarbons, is distilled from the coal by the passage of hot gases through the fuel column.

15 In the present process the air and steam used in making gas are preheated and then introduced into the blast zone of the fuel column to carry on reactions outlined above. The mixture of air and steam is heated in a pair of preheaters 20 which are so arranged that one preheater is used for preheating the mixture, while the other preheater is being heated by burning gas therein. When one preheater has been cooled to the minimum working temperature which is desirable, by 25 passing steam and air through it, the circulation of the steam and air mixture is stopped and then started in the other preheater which was being heated during the time when the first preheater was used for heating the mixture of steam and 30 air. To accomplish this air is introduced into one of the preheaters 24 through a pipe 26, and steam is supplied to the pipe 26 through a pipe 28. The steam and air mixture enters the top of an exhaust section 30 of the preheater, passes downwardly through a checker brick filling in the section 30, then through an opening 32 into the bottom of the main section of the preheater 24, and thence passes upwardly through a checker brick filling in the main section. In passing 35 through the two sections of the preheater the steam and air mixture becomes highly heated and it then flows through a blast neck 34 into a passage 36 surrounding the blast portion of the fuel column. From the passage 36 the mixture of 40 steam and air enters the fuel column, a portion of it forcing its way through the column to the bottom of the central off-take 20. In passing through the fuel column the fuel gas is made principally by the first three reactions outlined above, and the hot gas formed passes upwardly through the off-take in contact with a series of 45 superheating tubes 38, wherein water, vapor or steam to be used for the gas making operation is superheated before it is introduced through the 50 pipes 28 into sections 30 of preheaters 24. After passing through the off-take 20 the gas flows through outlets 40, Figs. 1 and 2, to a conduit 42 which conducts it to inlet flues 44 of waste heat 55 boilers 46 and 48. In the waste heat boilers 39 the hot gas passes upwardly through a series of tubes 50, Fig. 3, to a passage 52 at the top of the boiler, then downwardly through tubes 54 to an outlet flue 56, whence the gas passes 60 through a conduit 58 to a cooler of suitable construction, whereby the gas may be cooled and be ready to pass to the place of consumption or to the usual holder (not shown).

In normal operation of the gas generator the hot gas carried off through the off-take 20 is used to heat the boilers 46 and 48 simultaneously. If, however, one of the boilers needs to be cleaned or if one of the boilers gets out of order, all of the gas may be passed through one of the boilers at a time. To accomplish this a valve 60, Fig. 1, 75 is mounted in the inlet flue 44 in a position to

be moved into a valve seat 62 positioned at the bottom of the conduit 42. The valve 60 is mounted upon a rod 64 which moves through a stuffing box 66 positioned in the floor of the flue 44. To reciprocate the rod 64 through the stuffing box 80 a chain 68 is attached to the floor of the flue 44 and passes over pulleys 72 and 74, down to an operating platform.

When the preheater 24, for example, shown at the left of Fig. 1, is used for preheating the air and steam mixture, the preheater 24, shown at the right, is being heated by burning gas therein. At this time the preheater 24 at the right of Fig. 1 is cut off from the shaft 12 by means of a valve 76, and a portion of the gas from the conduit 58 is conducted through a pipe 78 and valve 80 into the top of the main section of the preheater.

At the same time air is introduced through an inlet 82, and the mixture of burning gas and air passes downwardly through the main section of the preheater, then upwardly through the exhaust section 30 of the preheater, and exhausts through an outlet 84. A cover 86 on the outlet 84 is open during the heating operation of the preheater, and the air and steam inlet pipes 26 and 28 are closed respectively by suitable valves 85 and 87 (Fig. 1).

The central off-take 20 which functions as a heat exchange means is supported on the top of the shaft 12 by the outlet pipes 40 and also by a series of braces 88 which are attached to the frame 90 of the generator. The inner lining of the off-take consists of the superheating tubes 38 which are connected between an inlet manifold 92 at the top, Figs. 1 and 2, a distributing manifold 94 at the bottom, and an outlet manifold 96 at the top. The steam to be superheated, is introduced into the inlet manifold 92 by means of a pipe 95 which connects with a steam header 97, mounted between the waste heat boilers 46 and 48. Suitable valves 98 and 100 are placed in the header 97 to control the flow of steam from the boilers. The steam flows from the inlet header 92 downwardly through tubes 38 to the header 94 and then upwardly through tubes to 105 the header 96 and out through a pipe 102, which preferably is connected with the sections 30 of the preheaters 24. Water is introduced into the waste heat boilers through inlet pipes 104. The waste heat boilers will abstract the larger portion of the heat from the fuel gas and this heat will normally produce a sufficient amount of steam to take care of the requirements of the gas making operation. However, the waste heat boilers may be supplemented with other steam boilers in making up the required amount of steam, so that one of the waste heat boilers may be shut down for any desired purpose.

By the time the fuel has moved downwardly through the carbonizing zone and reached the blast zone there is substantially no volatile material therein and therefore the gas which passes upwardly through the offtake 20 contains substantially no tar, ammonia, or other products which are usually formed in coal gas. Accordingly, the gas which leaves the waste heat boilers does not require any special purification.

The volatile material of the coal and other valuable by-products such as tars, oils and ammonia are removed from the coal by low temperature carbonization. To accomplish this, a small portion of the hot producer gas being made in the blast zone is led upwardly around the off-take 20 through the carbonizing zone of the fuel column to slowly distill off the by-products.

This small amount of gas containing the by-products passes into a peripheral outlet 106 at the top of the shaft, and flows through a conduit 108 which conducts it to the usual purification and treating equipment (not shown). In

5 this equipment the valuable by-products are removed and the purified gas may then be mixed with the gas passing through the outlet pipe 58. By this means substantially all of the valuable

10 by-products of the coal may be continuously removed and the coal converted into a coke or carbonized fuel which is very well suited for a blue water gas reaction. The gas containing the by-products is comparatively small in volume, compared with the entire gas output of the producer, and therefore the by-products may be recovered by treating a comparatively small amount of gas.

15 Although the temperatures used in the blast zone for making gas are comparatively high, these temperatures are not sufficiently high to slag or clinker the fuel, and therefore a comparatively large amount of the unburned fuel passes down to the bottom of the fuel column. This fuel is principally coke or carbonized fuel and

20 must be quenched to prevent destruction of the bottom of the shaft 12. To this end the unburned carbonized fuel and ash is supported in the bottom of the shaft upon a series of hoppers 110, Figs. 1, 4 and 5. The hoppers are preferably

25 made of a steel construction and are protected by refractory masonry lining. The hoppers, seven in number, consist of six peripheral hoppers, and a central hopper. An opening 112 is formed in the bottom of each of the peripheral hoppers, and an opening 114 is formed in the

30 central hopper. The central opening 114 is comparatively small and the material passes from the bottom of the column directly through this opening. The openings 112 are comparatively large and the material passing through these

35 openings flows upon a series of movable platforms 116, which are spaced from, but directly under the openings. The platforms 116 are arranged to be given a reciprocating motion by

40 means of water operated engines 118 to discharge the carbonized fuel from the platforms into a hopper 120 immediately below the hoppers 110. To cool the carbonized fuel passing down to the

45 hoppers 110 a water or steam pipe 122 is positioned below the hoppers and has an outlet 124 extending into each of the openings 112 and 114 by which water or steam may be directed into the carbonized fuel to quench and cool it. The water or steam introduced into the hot carbonized fuel passes upwardly through the fuel column in the form of vapor, thus acting to effectively cool the carbonized fuel in its upward passage. By the time the steam reaches the blast

50 zone it is highly preheated and enters into reaction with the carbonized fuel of the fuel column, so that it is utilized in making gas in the same way that the steam entering the fuel column through the preheater is used.

55 The carbonized fuel discharged from the hoppers 110 to the hopper 120 passes through a series of outlets 126 on the bottom of the hopper 120 and is collected in a chamber 128 at the bottom of the shaft. Periodically a door 130 at the bottom of the chamber 128 is opened and the carbonized

60 fuel accumulated therein may be drawn out. At the time the door 130 is opened to withdraw carbonized fuel from the chamber 128, doors 132 are moved into position to cover the outlets 126 by means of operating shafts 134 that extend to the

65 outside of the gas generating shaft 12. When the

door 130 is closed the doors 132 are opened to permit the carbonized fuel to pass from the hopper 120 to the chamber 128 and thus the carbonized fuel and ashes may be withdrawn from the bottom of the shaft without allowing gas to escape. To assist in moving the carbonized fuel through the hopper 120 a series of pokers 136 pass through the chamber 128 and the hopper 120, by which the carbonized fuel may be barreled and broken up while it is passing down to the openings 126 of the hopper 120.

70 An important feature of the present invention consists in giving a high degree of preheat to the mixture of air and steam being used for making gas whereby the inert material from the combustion of air may be retained in the gas while making a gas of comparatively high calorific value and high flame propagation. By preheating the steam and air the gas can be made with a lower percentage of air in proportion to the amount of steam used, and thus cut down the amount of inerts in the gas. This may be demonstrated as follows:

75 In the exothermic reaction between carbon and air when both the carbon and the air start cold, the following reaction takes place:

If, however, the air is preheated to 2000° F. and the carbon is preheated to 1500° F. a gain of substantially 6263 B. t. u. may be made.

80 In the endothermic reaction between carbon and water vapor on the basis that carbon is cold and steam is at 212° F., the reaction takes place as follows:

If, however, the steam is preheated to 2000° F. and the carbon is heated to 1500° F., a gain of approximately 4125 B. t. u. may be made.

85 The endothermic reaction between carbon and carbon-dioxide, assuming that both are cold, is substantially as follows:

If, however, the CO₂ is preheated to 2000° F. and the carbon is preheated to 1500° F. a gain of substantially 2725 B. t. u. may be effected. Assuming that the above reactions take place when the constituents are cold, as outlined above, a thermal heat balance may be obtained when the endothermic reaction between carbon and water vapor and the carbon and carbon dioxide constitutes 45% of the reaction, and the exothermic reaction between carbon and air constitutes 54.5% of the reaction. With such a combustion the analysis of the gas would be in percentages by volume.

B. t. u. value of gas per cubic foot = 75.5.

135

90 However, when assuming that the reactions take place, when the steam and air are heated to 2000° F. and the carbon is heated to 1500° F. a thermal heat balance will take place when 39% of the constituents enter into exothermic reactions, and 61% of the constituents enter into an endothermic reaction. Using the heat balance for the preheated materials, a gas formed by the combustion will analyze in percentages by volume:

B. t. u. value of gas per cubic foot = 108.

145

95 In other words, by preheating the steam, air, and carbon, the nitrogen content is reduced from 150

52 to 39.7%, the inerts are reduced from 77.2 to 66.9% and the calorific values increased from 74.5 to 108 B. t. u. per cubic foot. In the present process the degree of preheat depends strictly upon the 5 nature of the coal which is being treated, and, preferably will vary from 1200° F. to 2200° F. By preheating, a gas having a calorific value of from 200 to 225 B. t. u. per cubic foot may be produced which has most of the advantageous features of 10 water gas. The products of combustion of this gas will have a calorific value ranging from 80-90 B. t. u. per cubic foot even when no preheat is imparted to the blast air.

A typical analysis of a gas made by the present 15 process is substantially as follows:

In accordance with the character of the coal 20 being treated a gas may be made which will have a total amount of inerts of from 45 to 52 per cent. Furthermore by the low temperature carbonization applicant is able to gain a substantial amount in volume of methane produced and also gains 25 considerably in the amount of carbon monoxide and hydrogen produced which aid to increase the flame temperature and the flame propagation of the gas. The gas formed in carbonizing the coal above the blast zone has a comparatively high 30 heat value, and when this gas is blended with the gas taken off through the offtake 20, a gas is produced which when burned has a flame temperature ranging from 3000° F. to 3200° F. and is therefore suitable for practically all industrial 35 heating purposes.

With the process and apparatus outlined above, it will be seen that the manufacture of gas may be thoroughly controlled, and that the process will give a very good heat balance because the fuel 40 is introduced and removed from the generator substantially cold, and the residual heat in the gas is substantially all removed to the waste heat boiler. The heat of the gas is used for generating steam and for superheating the steam.

45 This case is a division of my copending patent application Serial No. 640,828, filed May 23, 1923, for "Manufacture of fuel gas", now matured as Patent 1,837,226, dated December 22, 1931.

The preferred form of the invention having 50 been thus described, what is claimed as new is:

I claim:

1. A gas generator comprising an upright shaft, means for introducing solid fuel to the upper portion of the shaft, means for removing carbonized 55 fuel and ashes from the lower portion of the shaft, a pair of preheaters, a pair of blast inlets respectively connecting the midportion of the shaft with the respective preheaters, a gas offtake mounted in the central portion of the shaft with an inlet adjacent the vertical midportion of the same, a steam superheater supported in the said gas offtake, a pair of waste-heat boilers, separate 60 valve-controlled means adapted to conduct gas from the said gas offtake to each of the said waste heat boilers, means for conducting away cool gas from each of the said boilers, and separate valve-controlled means connecting each of the said boilers with a corresponding preheater.

2. A gas generator comprising an upright shaft, 70 means for introducing solid fuel to the upper portion of the shaft, means for removing carbonized fuel and ashes from the lower portion of the shaft, a blast inlet connected to the midportion of the shaft, a centrally-disposed gas offtake in 75 the shaft with its inlet adjacent the vertical mid-

portion of the shaft, a peripheral gas off-take connected with the top portion of the shaft, a waste-heat boiler, valve-controlled indirect heat-exchange means including a steam superheater mounted in the first-mentioned gas offtake, and separate valve-controlled means respectively connecting the heat exchange means with the waste-heat boiler and with the said blast inlet. 80

3. A gas generator comprising an upright shaft, means for introducing solid fuel to the upper portion of the shaft, means for advancing the fuel through the shaft and for removing carbonized fuel and ashes from the lower portion of the shaft, a valve-controlled blast inlet connected to the vertical mid-portion of the shaft, a gas off-take in the central portion of the shaft with its inlet adjacent the vertical mid-portion of the shaft, a peripheral gas offtake connected with the top portion of the shaft, a waste heat boiler, indirect heat-exchange means including steam superheating elements mounted in the first-mentioned gas-offtake, and valve-controlled passages respectively connecting the heat-exchange means with the waste-heat boiler and with the said blast inlet. 90

4. A gas generator comprising an upright shaft, means for introducing solid fuel into the upper portion of the shaft, means for removing carbonized fuel and ashes from the lower portion of the shaft centrally thereof, a pair of independently-controlled blast inlets connected with the mid-portion of the shaft, a preheater connected with each blast inlet, a gas-offtake mounted in the central portion of the shaft with its inlet adjacent the vertical mid-portion of the shaft and substantially above the elevation of the said blast inlets, a pair of waste heat boilers, a heat-exchange unit mounted in the interior of the said gas off-take, independent valve-controlled means connecting the heat exchanger with the respective waste heat boilers, means connecting the said heat-exchanger with the respective preheaters, and separate means for respectively introducing gas and air for combustion into the respective preheaters. 105

5. A gas generator comprising an upright shaft, 110

means for introducing solid fuel into the upper portion of the shaft, means for removing carbonized fuel and ashes from the lower portion of the shaft centrally thereof, a pair of independently-controlled blast inlets connected with the mid-portion of the shaft, a preheater connected with each blast inlet, a gas-offtake mounted in the central portion of the shaft with its inlet adjacent the vertical mid-portion of the shaft and substantially above the elevation of the said blast inlets, a pair of waste-heat boilers, a heat-exchange unit mounted in the interior of the said gas offtake, independent valve-controlled means connecting the heat-exchanger with the respective waste-heat boilers, means connecting the said heat-exchanger with the respective preheaters, valve-controlled means connecting each waste-heat boiler with a corresponding preheater, and means for respectively introducing gas and air for combustion into the respective preheaters. 115

6. In gas generating apparatus, an upright gas 120

generator shaft having means near its base for supporting fuel in a column in the shaft and for advancing fuel therethrough at a controlled rate, a blast air inlet connected with the mid-portion 125 of the shaft, vertically-spaced axially and peripherally located gas offtakes respectively disposed at elevations above the said blast inlet, the said axially located gas offtake having its inlet end adjacent the vertical mid-portion of the shaft 130

and being adapted to withdraw highly heated combustible gases upwardly from the high temperature zone of a fuel column within the shaft while maintaining them out of direct contact with the said fuel, a fuel inlet in the top of the generator shaft, and means for directing the fuel downwardly around the said axial gas offtake.

7. Gas generating apparatus comprising an upright gas-generating shaft having means near its base for supporting fuel in a column therein and for advancing the same therethrough, a peripheral blast air inlet connected with the vertical mid-portion of the shaft, a fluid-jacketed conduit mounted in the upper portion of the shaft along

the longitudinal axis thereof and adapted to conduct highly heated combustion gases upward axially from the high temperature mid-portion of the shaft while maintaining them out of contact with solid fuel, a pair of heat regenerators, valve-controlled connections between the respective regenerators and the vertical mid-portion of the shaft, means in the upper part of the shaft for withdrawing combustible gases upwardly through the column of coal therein, and a pair of waste heat boilers, the said jacketed means being separately connected with the respective regenerators and with the respective waste heat boilers.
